DISH BRUSH

Leidy G. Scholl, Lansdale, Pa.

Application September 28, 1956, Serial No. 43,133

Term of patent 14 years

(Cl. D9—2)

Fig. 2

Fig. 1

Fig. 3

I claim:

The ornamental design for a dish brush, as shown.
